(Cl. D3—13)

Fig. 3.

Fig. 4.

Fig.5.

Fig.6.

FIG. 1 is a plan view of a scarf turban of my new design in unfastened or open condition, and with the cuff band folded flat;

FIG. 2 is a rear elevational view of the scarf turban of FIG. 1 in a wearing position with the cuff band portion in flat, doubled condition to form an open crown, the scarf ends tied in a loose knot at the back;

FIG. 3 is a fragmentary plan view of the scarf turban of FIG. 1 showing the opposite face thereof, and with the cuff partially raised or open;

FIG. 4 is another rear elevational view of the scarf of FIG. 1 with the cuff raised or opened to form a crown, the scarf being tied in a bow at the back;

FIG. 5 is a fragmentary plan view of the scarf turban of FIG. 1 with the cuff turned inside out and partially elevated; and

FIG. 6 is a front perspective view of the scarf turban of FIG. 1 in fastened condition with the cuff folded flat and a portion broken away.

I claim:

The ornamental design for a scarf turban, as shown.
